UNITED STATES PATENT OFFICE.

JOHN J. TOKHEIM, OF CEDAR RAPIDS, IOWA.

BOTTLE-CAPPER.

1,376,906.

Specification of Letters Patent.

Patented May 3, 1921.

Application filed August 28, 1919. Serial No. 320,408.

To all whom it may concern:

Be it known that I, JOHN J. TOKHEIM, a citizen of the United States, residing at Cedar Rapids, in the county of Linn and State 5 of Iowa, have invented a new and useful Bottle-Capper, of which the following is a specification.

This invention relates to a device for use in placing metal caps on bottles, one of its 10 objects being to provide a simple, compact and efficient device of this character which can be operated readily and which has means for firmly gripping the neck of the bottle while the cap is being forced to position.

15 Another object is to provide a device of the class mentioned which is formed of few parts and will not readily get out of order.

With the foregoing and other objects in view which will appear as the description 20 proceeds, the invention consists of certain novel details of construction and combinations of parts which will be hereinafter more fully described and pointed out in the claims, it being understood that various 25 changes may be made in the construction and arrangement of the parts without departing from the spirit or sacrificing any of the advantages of the invention as set forth in the appended claims.

30 In the accompanying drawings the preferred form of the invention has been shown.

In said drawings—

Figure 1 is a side elevation of the capper in use, one of the handles being broken away.

35 Fig. 2 is a plan view.

Referring to the figures by characters of reference, 1 designates a cup like die adapted to receive a metal or "crown" cap and to force it upon and shape it around the 40 flanged mouth portion *a* of a bottle neck *A*. This die is of the usual construction. It has ears 2 upstanding therefrom and pivotally connected to these ears is the middle portion of the tension yoke 3. To the ends of this 45 yoke are pivotally connected levers 4 having long arms 5 constituting handles and short arms 6 to which are pivotally connected neck gripping jaws 7.

In using the device a cap is placed on the 50 neck of the bottle and the levers 4 are swung so as to move the jaws 7 apart and permit

them to be placed at opposite sides of the bottle neck. The long arms of both levers are then thrust downwardly and will cause the jaws 7 to firmly embrace the bottle neck 55 and to come together as shown. The die 1 will be pulled downwardly by the levers drawing on the yoke and will engage and shape the cap so as to bind it on the bottle neck. During the foregoing action the 60 points of connection between the yoke 3 and the levers 4 will move downwardly past the dead centers so that the parts will be held firmly assembled until the levers 4 are pulled upwardly to restore the parts of the tool to 65 their initial position and release the bottle from the jaws.

Importance is attached to the use of the spring yoke 3 because it holds the jaws together until the capper head or die is lifted 70 off of the bottle after the cap has been put on.

What is claimed is:—

1. A capper including a tension yoke, a capper head connected to an intermediate 75 portion thereof, levers connected to the terminals of the yoke, and bottle gripping jaws connected to the levers.

2. A capper including opposed levers, gripping jaws pivotally connected thereto, a spring yoke connected at its ends to the levers, and a capper head pivotally connected to the yoke, said levers being movable to carry the points of connection between the levers and yoke downwardly past their dead 85 centers to lower and hold the capping head in active position.

3. A capper including opposed jaws, a tension yoke, a lever connection between each end of the yoke and one of the jaws, 90 and a capper head carried by the yoke, said yoke constituting tension means for holding the jaws together until the capper head is lifted off of an engaged bottle cap.

In testimony that I claim the foregoing 95 as my own, I have hereto affixed my signature in the presence of two witnesses.

JOHN J. TOKHEIM.
